CLAIM

The ornamental design for the recessed shower receptacle, as shown and described.

DESCRIPTION

FIG. 1 is a top, front and side perspective view of a recessed shower receptacle showing my new design showing the lid in an open position;

FIG. 2 is a top and side perspective view thereof;

FIG. 3 is a side and top perspective view thereof;

FIG. 4 is a top plan view thereof showing the lid in a closed position;

FIG. 5 is a side elevation view thereof, showing the lid in a closed position, the rear and side views being the same apart from the orientation of the tab and rear hinge;

FIG. 6 is a top plan view thereof showing the lid in an open position; and,

FIG. 7 is a bottom plan view thereof showing the lid in a closed position.

The broken line showing of a shower handle and panel portion to which the receptacle is mounted is for illustrative purposes only and forms no part of the claimed design.
